United States Patent Office

Des. 226,631
Patented Apr. 3, 1973

226,631

TIMER

Jack F. Baker, Glenview, and Robert W. Fee, Oak Park,
Ill., assignors to AMF Incorporated

Filed May 5, 1971, Ser. No. 140,649

Term of patent 14 years

Int. Cl. D10—03

U.S. Cl. D42—7 R

FIG. 1

FIG. 2

FIG. 3

FIG. 4

FIG. 1 is a perspective view of a timer showing our new design;

FIG. 2 is a top plan view thereof;

FIG. 3 is a bottom plan view thereof;

FIG. 4 is a rear elevational view of FIG. 1 with a portion broken away to more clearly show the cross-sectional shape of the annular base.

We claim:

The ornamental design for a timer, substantially as shown and described.
